James Wager, Troy, New York.
Letters Patent No 242, dated Oct 23 1829.

The Schedule referred to in these Letters Patent and
making part of the ~~same~~

To all to whom these presents shall come:

Be it known, that I, James Wager, of Troy, in the County of Rensselaer, and State of New York, have invented or produced a new design for, Parlour Stoves, and I do hereby declare that the following is a full and exact description of the same. In the accompanying drawings,

Figure 1. is a plan of a section of the bottom plate of the stove.

Figure 2. is a plan of a section of the top plate.

Figure 3. is a plan of a section of the end plate.

Figure 4. is a plan of a section of the front plate and one of the doors.

Figure 5. a plan of a section of the urn.

Figure 6. " " of one of the feet.

Figure 7. " " of a section of the moveable top of the urn.

The bottom plate (a) (fig 1.) of the stove is ornamented with a border in the Grecian style, and the body of it is decorated with foliated tracery in cyma recta and cyma-reversa curves, and where the said bottom plate is joined by the upright plates of the stove, it is provided with an ornamented

moulding arranged in concave lines to correspond with the form of the other plates of the stone. From the four corners of the bottom plate rise columns which are ornamented about midway with a meath.

The side plates (n) (See fig 3), of the stone are gothic channelled and ornamented with a Corinthian border, and the channels filled with gothic tracery. The top plate (d) (See fig 2.) is elaborately decorated by several concentric borders of cyma-recta and cyma-reversa tracery, with a slightly elevated ornament immediately over each column; the interior is ornamented with leaves and in the centre there are concave concentric mouldings and fillets.

The top of the front plate (s) (See fig 4) has a Roman moulding, (seen in figure 3) and another around the base. At 3 is given the outline of the figure which is to be filled up as in figure 3. Around the sides and top and down the middle of the front plate, dividing it in two equal parts, is a Corinthian border, like that seen in the side plate fig 3. the doors (h) are gothic channelled and ornamented in the gothic style. The feet (i) (See fig 6), are composed of a lions head, legs, and claws.

What I claim and desire to secure by Letters Patent, are the above described and illustrated designs for stones.
